METHOD OF OPENING OYSTERS

John W. Pogany, Port Townsend, Wash.

Application November 16, 1948, Serial No. 60,275

2 Claims. (Cl. 17—45)

1

This invention relates to a method of and means for the opening of oysters, clams, mollusks and the like; and it has for its principal object to provide a simple and effective method whereby large quantities of such bivalves may be simultaneously opened without heating or cooking and without requiring use of hand tools or manually operated devices usually employed for that purpose and requiring individual handling of the oyster, or other bivalve.

More specifically stated, the invention resides in the use of vacuum to effect the opening of the bivalve and the breaking of the muscle that ordinarily holds the shell closed and the meat in the shell.

A further object resides in the provision of a novel apparatus to be used in the practising of the present method.

In accomplishing the above mentioned and other objects of the invention, I have provided an apparatus having improved details of construction, the preferred forms of which are illustrated in the accompanying drawings, wherein:

Fig. 1 is a perspective view of an apparatus for the opening of oysters, and the like, in accordance with the objects of the present invention.

Fig. 2 is a vertical longitudinal section of the apparatus.

Fig. 3 is a top or plan view of the same.

Fig. 4 is a sectional detail of a part of the apparatus.

Referring more in detail to the drawings:

The present method of opening oysters, clams, and other bivalves, anticipates that a large quantity thereof be placed in a chamber, the chamber sealed and vacuum applied thereto to whatever extent is necessary to cause the bivalves to open. Then, after the application of vacuum for a length of time sufficient that all under treatment at the time will have been fully opened, a sudden change in pressure condition is effected by breaking the vacuum seal that results in killing the oyster by tearing the shell contracting muscle, thus permitting easy removal of the raw meat from the shells.

The means whereby this method can be expeditiously and effectively accomplished, and as shown in accompanying drawings, comprises a vacuum or decompression chamber 10, here illustrated as being a boxlike enclosure of rectangular form, supported at a suitable working height by legs 11. Preferably this chamber is made from sheet steel of such thickness as to adequately withstand the pressure to which it will be subjected. However, it might well be made of other material.

2

In the top wall 10a of the chamber is an opening 12 over which a lid or door 13 is adapted to be closed, as has been shown best in Fig. 2. The door is attached at one edge by hinges 14, to swing upwardly to open position as indicated in dotted lines and, when closed, it seats tightly against a sealing gasket 15 as shown best in Fig. 4. In the bottom wall 10b of the chamber, is an opening 16, over which a lid or door 18 may be closed. This door is attached by hinges 19 and, as indicated, swings downwardly to open position. When the door is closed, it is seated against a sealing gasket 20. The chamber is charged with the oysters, clams, or the like, through the top opening 12, and after they have been subjected to vacuum, they are discharged through the opening 16 in the bottom wall by opening the door 18.

In their closed positions, the doors 13 and 18 may be held tightly sealed by latches or dogs 22 that are pivoted on the side walls of the chamber and adapted to be holdingly engaged with studs or lugs 23 fixed to and extending outwardly from the side edges of the doors as indicated in Fig. 4.

Opening into the vacuum chamber, preferably through the rear end wall, 10d, is a suction pipe 25 leading to a suction pump or other suitable source of vacuum. This is equipped with control valve 26. Mounted in the top wall 10a of the chamber is a vacuum release valve 30 with control lever 31 for opening or closing the valve. Also, it is desirable, in order that the action on bivalves being treated can be noted, that observation panels 33 of glass or other suitable transparent material be set in openings 35 in the side walls of the chamber, as has been shown in Figs. 1 and 4, and also that a vacuum indicating gauge 36 be mounted in a side wall to show the degree of vacuum that is being applied at any time.

Mounted in the supporting leg structure of the chamber, directly below the chamber 10, is a receiving chute or plate 40. This is downwardly inclined and has a flat bottom formed with opposite side flanges and a flange across the higher end. The bottom plate also is closely perforated to drain off water, but to retain the opened oysters when they are discharged from the chamber upon opening the door 18. The lower end of the trough or chute is open and preferably terminates in a horizontal flange 42. A receptacle may be placed below the lower end of this chute to catch the opened oysters.

To carry out the process, the bottom door of the chamber is closed and sealed. The top door is opened and a charge of fresh oysters is poured into the chamber 10. Then the top door is closed

and sealed. Vacuum is then applied by opening the valve 26 and the degree of vacuum can be noted by reference to gauge 36.

Under the effect of vacuum, the oysters will open, and this opening action can be observed by looking through the transparent panels 33. When all are open, vacuum valve 26 is closed and valve 30 is opened, thus suddenly releasing the vacuum. This has been found to cause the breaking of the shell-closing muscle and the killing of the oyster.

The opened oysters are then discharged from the chamber by opening the bottom door. They fall onto chute 40 and from there pass into the receiving receptacle, water draining off through the trough perforations.

The above method is simple, effective, quick and inexpensive. It eliminates the tedious hand opening operations and is practical for all kinds of bivalves.

In the following claims the word "oysters" is intended to designate all bivalves for which the device and method is applicable.

Having thus described my invention, what I

claim as new therein and desire to secure by Letters Patent is:

1. A method of opening oysters and other bivalves comprising confining the fresh oysters within an air-tight chamber and subjecting the chamber to vacuum, until the oysters have opened.

2. A method of opening oysters and other bivalves comprising confining the fresh oysters in an air-tight chamber, subjecting the chamber to vacuum, until the oysters have opened, then quickly releasing the vacuum.

JOHN W. POGANY.
